(57) **CLAIM**

The ornamental design for a power strip stand, as shown and described.

DESCRIPTION

FIG. 1 is an angled side perspective view of a power strip stand;

FIG. 2 is a front view thereof;

FIG. 3 is a rear view thereof;

FIG. 4 is a side view thereof;

FIG. 5 is an opposing side view thereof;

FIG. 6 is a top view thereof;

FIG. 7 is a bottom view thereof; and,

FIG. 8 is a perspective view thereof in an environment of use.

The broken lines depict portions of the claimed design or environment that form no part of the claimed design.
